UNITED STATES PATENT OFFICE

WILTON RUBINSTEIN, OF ST. LOUIS, MISSOURI

COLLAR FASTENER

Application filed May 6, 1929. Serial No. 360,882.

This invention relates to collar fasteners and has special reference to a construction and formation of a detached collar and a device for use in connection with the collar whereby the necessity of using a button or like fastener for holding the ends of the collar together is eliminated.

An object of the invention is to provide a shirt collar of the detached type having 10 on one end means for engaging with a button in connection with the collar band, in combination with a device applicable to the collar for holding the ends in proper relationship and which permits free adjustment 15 of the collar as to size.

Another object of the invention is to provide an improved shirt collar having means on one end for engagement with a button on the neck band of a shirt and having a 20 device in connection with the opposite end for engaging the opposite end of the neck band of the shirt and also for engaging the collar to hold the ends of the neck band and the collar respectively in proper relationship and which has sliding engagement 25 with the collar to permit free expansion and adjustment of the collar.

Another object of the invention is to provide a flexible and resilient tab for use in 30 connection with the ends of the collar for holding the collar in proper relationship without attachment of both ends of the collar to the neck band of the shirt.

Various other objects and advantages of 35 my improved shirt collar will appear from the following description, reference being made to the accompanying drawings in which,

Fig. 1 is a view showing my improved 40 collar in connection with the neck band of a shirt, the ends of the collar being spread apart to show the construction of the inner side of the collar band.

Fig. 2 is a view showing one end of the 45 collar attached to the button on the neck band of the shirt, the other end of the collar being rolled away.

Fig. 3 is a view showing the manner in 50 which the tab engages the ends of the collar,

the ends of the collar being slightly spread apart clearly to show the tab.

Fig. 4 is a sectional view showing the ends of the collar held together by my improved 55 collar tab.

Fig. 5 is a front view similar to Fig. 1 showing a construction whereby the ends of the neck band of the shirt may be detached from each other and connected only to the respective ends of the collar. 60

Fig. 6 is a view showing the tab engaging an adjacent end of the neck band of the shirt and also the end of the collar opposite from the end on which the tab is mounted.

Fig. 7 is a front view showing the collar 65 in closed position in which it will be retained by my improved tab.

Fig. 8 is a sectional view showing the ends of the neck band detached from each other but secured to the collar by my improved 70 tab.

Fig. 9 is a side elevation of my improved resilient tab.

In the embodiment of the invention shown in Figs. 1 to 4, inclusive, the collar is of 75 the roll or turned down type comprising an outer section 1 and an inner section or band. The inner section or band comprises a ply 2, a ply 3 and a lining 4 located between the plies 2 and 3. The ply 2 near one end of the collar is formed with a buttonhole 5 designed and adapted to be engaged with the collar button 6 for holding together the ends of the neck band 7 of the shirt. 80

The ply 3 is formed with a slit 8 from which a pocket extends in a direction away from the end of the collar, said pocket being defined by stitches 9. 85

The opposite end of the collar as shown 90 is not provided with any button hole for engaging the button 6, although such a buttonhole may be included in the collar construction if desired. A slit 10 is formed in the ply 2, the same entering a pocket defined by stitches 11. Another slit 12 of greater length than the slit 10 enters the pocket formed by the stitches 11 between the slit 10 and the end row of stitches 13 for the pocket. 95

These pockets formed by the stitches 9 and 11 are preferably curved so as to conform approximately with the shape of the tab by which the ends of the collar are adjustably connected. The tab comprises an elongated curved resilient member having at one end a wide portion 14 and at the opposite end a narrow portion 15, the union of the wide portion 14 with the narrow portion 15 being defined by abrupt shoulders 16 on the upper and lower edges of the tab.

In use the tab is inserted into the pocket defined by the stitches 11, the narrow end of the tab being passed through the slit 12 and thence through between the rows of stitches 11 and extending outwardly through the slit 10. The part 14 of the tab is too wide to pass through the slit 10 but may pass into the pocket through the slit 12. The shoulders 16 engage against the end of the pocket above and below the ends of the slit 10 and prevent the tab from slipping out. The opposite end of the tab preferably extends beyond the slit 12 so that it will not work out, although this latter arrangement is not essential because the tie will prevent the tab from working out through the slit 12. The projecting end 15 of the tab is then inserted through the slit 8 into the pocket formed by the stitches 9. This tab is quite flexible and yet is of sufficient stiffness to support the ends of the collar in proper and neat form and prevent them from sagging. It permits the collar to be adjusted as to size and the collar will be prevented by the tie from expanding beyond the desired size. The tab is easily insertable and withdrawable and should be removed before the shirt is laundered.

In the embodiment shown in Figs. 5 to 8, inclusive, the collar is of precisely the same construction as that above described and like reference numerals are applied thereto. As there shown, the collar button 6 may be engaged in the buttonhole 5 but the opposite end of the neck band of the shirt is not engaged with said button 6 but is provided with a loop 17 through which the end 15 of the tab is passed. Thus, when the ends of the collar are connected together and with the ends of the neck band of the shirt, the neck bands of the shirt are not connected by the button 6 but are freely adjustable with the collar as to size. When the collar is connected by inserting the tab 15 in the loop 17 and in connection with the opposite end of the collar, all of the parts will be held in proper relationship and the collar will be prevented from expanding beyond the desired shape by the tie.

From the foregoing it must be apparent that the invention obtains all of its intended objects and purposes in a highly efficient and satisfactory manner. Obviously, the

invention may be varied within equivalent limits without departure from the nature and principle thereof.

I do not restrict myself unessentially in any particulars, but what I claim and desire to secure by Letters Patent is:—

1. In a collar, means forming a pocket near one end of the collar, said pocket having spaced slits therein opening to the inside of the collar, a tab insertable in and withdrawable from said pocket and arranged to have one end projecting beyond the end of the collar, and means forming a pocket in the opposite end of the collar with a slit opening outwardly for receiving the projecting end of said tab.

2. In a collar, a collar band comprising a number of plies of material, the inner ply of material being supplied with a button-hole near its end, means forming a pocket in the opposite end of the collar band with spaced slits therein of which one of said slits opens inwardly, a tab insertable in and withdrawable from said pocket and arranged to have one end projecting beyond the end of said collar band, means forming a pocket in the opposite end of the band with a slit on the outside of the band for receiving the projecting end of said tab, and means preventing outward withdrawal of said tab from said pocket in which said tab is mounted and permitting sliding adjustment of the ends of the collar.

3. In a collar, a collar band having a buttonhole in one end for engagement with a collar button, a pocket formed in the opposite end of the collar band and having an opening to the inside of the collar band near the end of said band, a tab mounted in said pocket and having its upper and lower edges curving approximately with the curvature of the upper and lower edges of the collar band, and means forming a pocket in the opposite end of the collar for receiving the end of said tab.

4. In a collar, a collar band having a buttonhole in one end for engagement with a collar button, a pocket formed in the opposite end of the collar band and having an opening to the inside of the collar band near the end of said band, a tab mounted in said pocket and having its upper and lower edges curving approximately with the curvature of the upper and lower edges of the collar band, means forming a pocket in the opposite end of the collar for receiving the end of said tab, and means limiting extent of longitudinal movement of said tab in both directions.

5. A collar comprising a collar band having a buttonhole near one end for engaging with a collar button, a tab, means detachably supporting said tab in connection with the opposite end of said band in a relationship in which said tab projects beyond the

end of said band, and means forming a pocket in the opposite end of the band for receiving said projecting end of said tab.

6. A collar comprising a collar band having a buttonhole near one end for engaging with a collar button, a tab, means detachably supporting said tab in connection with the opposite end of said band in a relationship in which said tab projects beyond the end of said band, means forming a pocket in the opposite end of the band for receiving said projecting end of said tab, and means limiting extent of longitudinal movement of said tab in both directions.

7. A detached collar for a shirt comprising a collar band having a buttonhole near one end for engagement with the collar button of the shirt, a resilient tab, a pocket in the opposite end of said band removably supporting said tab in a relationship in which one end of said tab projects beyond the end of said band, and a pocket in the end of the collar band that is provided with said buttonhole for receiving said projecting end of said resilient tab.

8. A detached collar for a shirt comprising a collar band having a buttonhole near one end for engagement with the collar button of the shirt, a resilient tab, a pocket in the opposite end of said band removably supporting said tab in a relationship in which one end of said tab projects beyond the end of said band, a pocket in the end of the collar band that is provided with said buttonhole for receiving said projecting end of said resilient tab, and means limiting extent of longitudinal movement of said tab in both directions and permitting detachment of said tab from said band.

9. A detachable shirt collar comprising a collar band including an inner ply and an outer ply and having a buttonhole through the inner ply covered by said outer ply and having a pocket in the opposite end between said plies and provided with a slit opening through the inner ply adjacent to the end of the band, and means forming a pocket within the outer ply at the opposite end of the collar with a slit opening through said outer ply, in combination with a tab located in said first named pocket and having a projecting end for insertion in and withdrawal from said second pocket through said slit opening into said second pocket.

10. The combination with the neckband of a shirt, a button in connection with one end of said band, and a loop in connection with the opposite end of said band, of a detachable collar having a buttonhole near one end for engagement with said button and having pockets in its opposite ends, a tab mounted in one of said pockets and having its end projecting beyond the end of the collar for insertion in the pocket in the opposite end of said collar, and means limiting extent of

longitudinal movements of said tab in both directions.

11. A collar comprising a collar band having a button hole therethrough in one end for engagement with a collar button and having in one end a pocket provided with a slit opening only to the inner side of the collar band and said collar band having in the opposite end a pocket provided with a slit opening only to the outer side of the collar band, in combination with a tab insertable in and withdrawable from said pocket in the end of the collar band that is opposite from the end having said button hole in a relationship in which the end of said tab projects a sufficient distance for insertion in said pocket in the end of said collar band having said button hole.

12. A collar comprising a collar band having a button hole therethrough in one end for engagement with a collar button and having in one end a pocket provided with a slit opening only to the inner side of the collar band and said collar band having in the opposite end a pocket provided with a slit opening only to the outer side of the collar band, in combination with a tab insertable in and withdrawable from said pocket in the end of the collar band that is opposite from the end having said button hole in a relationship in which the end of said tab projects a sufficient distance for insertion in said pocket in the end of said collar band having said button hole, and means preventing said tab from being withdrawn outwardly from said first named pocket in which it is placed.

13. A collar comprising a multi-ply collar band arranged to encircle the neckband of a shirt and having between the plies near one end of the collar band a pocket and a slit opening from said pocket through the inner ply of the collar band only and having in the opposite end of the collar band a pocket and a slit opening from said pocket to the outer ply of the collar band only, in combination with a tab insertable in and withdrawable from said first named pocket and arranged to extend beyond the end of the collar band having the pocket in which said tab is mounted and to be inserted through said slit that opens from the outer side of the collar band into said second pocket.
